FURNACE DOORFRAME

Herman W. Wilson, Cleveland Heights, Ohio, assignor to Republic Steel Corporation, Cleveland, Ohio, a corporation of New Jersey

Application November 29, 1945, Serial No. 631,597

6 Claims. (Cl. 122—499)

1

This invention relates generally to the furnace art and particularly to a new door frame for open hearth furnaces.

Door frames, particularly those of open hearth furnaces, are subjected in use to severe service conditions. They are exposed to high temperatures from the inside of the furnace and to much lower temperatures from the outside of the furnace, and this temperature differential is much greater while the door is open than when it is closed.

The expansion and contraction of the side legs of the frame during the operation of the furnace is considerable in extent and when such expansion and contraction is opposed by the brickwork or buck staves of the furnace these legs may bow away from the buck staves and leave openings thru which flames or highly heated gases may escape. Also, buckling of the side legs of the frame, due to restraints imposed on their expansion and contraction may cause the legs to bow outwardly of the furnace and thus prevent the door from sealing the door opening against escape of flames and hot gases.

Since charging boxes are passed thru the opening in the door frame, they frequently strike or bump against the side legs of the door frame and may damage the legs or loosen the brick-work around them.

Many efforts have been made heretofore to provide open hearth door frames which would not possess these several important disadvantages but, so far as I know, none of these efforts has been entirely satisfactory.

According to the present invention I have provided an open hearth door frame which may be fluid cooled and thereby maintained at a reasonably low operating temperature, which is highly resistant to damage by impacts received from the charging boxes or parts of the charge, which can expand and contract without buckling or bowing of the side legs, and which is low in construction and maintenance costs. Door frames embodying the present invention have proven to be highly satisfactory in actual commercial use.

In the drawings accompanying and forming a part of this specification,

Fig. 1 is a front elevational view of one embodiment of the present invention;

Fig. 2 is a top plan view of the door of Fig. 1;

Fig. 3 is a bottom plan view of the door of Fig. 1;

Fig. 4 is a fragmentary cross-sectional view taken on line 4—4 of Fig. 1; and,

2

Fig. 5 is a cross-sectional view taken on line 5—5 of Fig. 1.

The door frame shown in Figs. 1 to 5 comprises tubular side legs 1 and 2, a tubular sill 3 connected at its ends to the lower ends of legs 1 and 2, a lintel 4 disposed between legs 1 and 2, a pipe 5 connecting sill 3 with the upper end of side leg 1, and solid plates connecting lintel 4 and pipe 5 to legs 1 and 2. One of these plates 6 is connected to the upper side of lintel 4 near one end thereof, and to the side of the upper portion of leg 2 thereabove. Both connections may be made by welding the plate 6 to lintel 4 and leg 2. Another plate 7 is similarly connected to the upper portion of lintel 4 near its opposite end and to leg 1. At its upper end plate 7 is connected to the under side of pipe 5. Plate 8 is connected to the upper side of tube 5 and to the adjacent part of leg 1.

Leg 1 is provided with a vent 9 at its upper end a clean-out plug 10 at its lower end. Leg 2 is provided with a clean-out plug 11 near its lower end and an outlet connection 12 at its upper end.

Plate 13 is connected, as by welding, to pipe 5 as indicated and is provided with a hole 14 thru which a lifting hook may be inserted. It will be noted that hole 14 is disposed midway between legs 1 and 2 so that the frame will be in balance when suspended on a hook extending thru hole 14.

Lintel 4 is hollow and is preferably made by flattening a heavy weld metal tube, as is better shown in Fig. 5. Its ends are closed by curved plates 15 which have outer concave surfaces corresponding generally to the opposed surfaces of legs 1 and 2. These plates 15 are preferably secured in place in the lintel by weld metal 16. Opening 17 permits access to the interior of the lintel for cleaning purposes. Lintel 4 has an inlet connection 20 to be attached to a source of cooling liquid, such as water. Between this inlet 20 and the connection of pipe 5 to lintel 4 a vertical baffle 21 extends downwardly within the lintel and at its lower end is connected to a horizontally extending baffle 22 which stops short of the end plates 15 of the lintel. Thus the baffles 21 and 22 direct liquid entering thru inlet 20 along the top of baffle 21 to one end of the lintel, thence down into the lower portion of the lintel and therealong toward the outer end thereof, up past the end of baffle 21 and into pipe 5. A vent hole 23 in baffle 21 permits equalization of pressure on opposite sides thereof.

Since the interior of lintel 4, pipe 5, leg 1,

sill 3 and leg 2 are in communication, liquid brought into the lintel thru inlet 20 may flow successively and rapidly thru these parts and out thru discharge outlet 12. In this manner the temperature of these frame parts is maintained fairly constant and sufficiently low so that excessive contraction and expansion of these frame parts is minimized.

It will be understood from the foregoing description that the legs 1 and 2 and sill 3 constitute what may be considered as U-shaped structure which can be deflected by moving the upper ends of the legs toward or away from each other and that lintel 4, and pipe 5, may be considered as a suspended structure which is expandable and contractible and which is connected to the opposed sides of legs 1 and 2 by plates 6, 7 and 8. The legs of the U-shaped structure may be moved toward or away from each other to a limited extent by the expansion and contraction of the suspended structure. The end plates 15 of lintel 4 are disposed adjacent to but are not connected directly to legs 1 and 2. On the contrary, they are spaced far enough away from those legs so that lintel 4 may expand thruout the normally expected temperature range, in which it is desirably maintained, without exerting forces on legs 1 and 2 which would materially distort those legs. If and when the expansion or contraction of lintel 4 is unexpectedly large the upper ends of these legs may move relative to each other without resultant serious bowing or buckling of the legs.

It will also be understood that legs 1 and 2 may expand and contract lengthwise without substantial restriction being imposed thereon by lintel 5 and the other parts of the suspended structure. Thus buckling or bowing of the legs is avoided.

Frames embodying the present invention are resistant to serious damage in use. The sill 3 is preferably covered over with several inches of brickwork and hence does not come into contact with the charging boxes. Legs 1 and 2, consisting of heavy pipe, present only curved surfaces to the charging boxes and by being kept cool with liquid flowing rapidly therethru are strong enough to resist damage caused by impact of the boxes or their contents therewith. Preferably, these side legs are protected at least on their inner sides by the furnace brickwork and, since these legs are prevented from substantial buckling or bowing, they do not dislodge such brickwork or pull away from the adjacent buck staves of the furnace.

The construction of the lintel is such that it is strong, and even tho the charging boxes should come into contact forcibly with it it is capable of resisting heavy impact forces received from that source. The fact that the lintel is not welded to the side legs eliminates any danger of breakage of welded joints due to impact of the charging boxes with either the side legs or the lintel, or due to relative movement of the lintel and legs.

Since it is contemplated that cooling liquid will flow rapidly thru the frame, there is little opportunity for sediment to deposit in the parts thereof but any sediment which does deposit may be readily removed by taking out plugs 10 and 11 and flushing out the sediment.

It will be understood from the foregoing description that the present invention provides a highly efficient, strong and durable door frame for an open hearth furnace and one which can be maintained in substantially continuous opera-

tion and is easy to construct and maintain and is comparatively inexpensive in cost of construction.

Having thus described my invention so that others skilled in the art may be able to understand and practice the same, I state that what I desire to secure by Letters Patent is defined in what is claimed.

What is claimed is:

1. A liquid cooled furnace door frame comprising side legs, a sill connected at its ends to the lower ends of said legs, a lintel having closed ends disposed adjacent to said side legs and a liquid inlet, a pipe connecting said lintel and one of said legs, and solid, lintel suspending means welded to the top of said lintel near its ends and welded to and supported by portions of the side legs above the lintel, said legs, sill, lintel and pipe being hollow and defining a continuous passage for cooling liquid.
2. A liquid cooled furnace door frame comprising side legs, a sill connected at its ends to the lower ends of said legs, a lintel having ends disposed adjacent to said side legs, a hollow member connecting the upper mid-portion of the lintel to the upper end portion of one side leg, and lintel suspending means connected to the upper portions of said lintel near its ends and to portions of the side legs thereabove, said side legs, sill, lintel and hollow member defining a continuous passage for cooling liquid.
3. A liquid cooled furnace door frame comprising tubular side legs, a tubular sill connected at its ends to the lower ends of said legs, a flattened tubular lintel having ends disposed adjacent to said side legs and having a baffle therewithin, a tubular connection from the lintel on one side of said baffle to one of said legs, said lintel having a liquid inlet opening on the opposite side of said baffle, the other of said legs having a liquid outlet opening at its upper end, and lintel suspending means connected to the upper portions of said lintel near its ends and to portions of the side legs thereabove, said side legs, sill, lintel and tubular connection defining a passage for flow of cooling liquid thru said frame.
4. A liquid cooled furnace door frame comprising a U-shaped structure including side legs and a sill integrally connected at its ends to the lower ends of said legs and an expandable and contractible structure suspended within the upper part of said U-shaped structure, said suspended structure including a lintel having closed ends disposed adjacent to said side legs and suspending means welded to the upper portions of said lintel near its ends and to portions of the side legs thereabove, each of said structures being capable of expansion and contraction relative to the other of said structures without causing substantial distortion of said other structure, a tube connecting the interiors of the lintel and one side leg, said side legs, sill, lintel and tube defining a passage for flow of cooling liquid through said frame.
5. A liquid cooled lintel for a furnace door frame comprising a hollow member having closures, its ends concavely shaped to correspond to and slidably engage the convex surfaces of side frame members, said lintel having inlet and outlet openings at the upper side of said member and baffles therewithin to direct flow of liquid from said inlet opening lengthwise along the lower portions of said lintel and upwardly to said outlet opening, and solid suspension plates connected to the upper side of said lintel near its ends and connectible to side frame members.
6. A liquid cooled lintel for a furnace door

frame comprising a hollow member having closures at its ends concavely shaped to correspond to and slidably engage with the convex outer surfaces of side frame members, said lintel having inlet and outlet openings at the upper side thereof, a vertical baffle depending between said openings and a horizontal baffle connected to said vertical baffle and extending toward the ends of said lintel, said baffles serving to direct the flow of liquid from said inlet opening lengthwise along the lower portion of said lintel and upwardly to said outlet opening.
